CLAIM

The ornamental design for an extendable cup with lid, as shown and described.

DESCRIPTION

1. Extendable cup with lid

1.1 : Front

1.2 : Back

1.3 : Left

1.4 : Right

1.5 : Top

1.6 : Bottom

1.7 : Perspective

1.8 : Front view 1 of state of use

1.9 : Front view 2 of state of use

This design is an extendable cup shown in reproductions 1.1 to 1.9; reproductions 1.1 to 1.7 show the cup in a fully expanded state, while reproductions 1.8 and 1.9 show the cup in two changing states, in particular: reproduction 1.8

(Continued)

shows the cup in a partially compressed state, and reproduction 1.9 shows the cup in a completely compressed state.

1 Claim, 9 Drawing Sheets
